UNITED STATES PATENT OFFICE

LAURENT H. WILD, OF AUDUBON, NEW JERSEY, ASSIGNOR TO THE METROPOLITAN SEWING MACHINE CORPORATION, OF NYACK, NEW YORK, A CORPORATION OF DELAWARE

STITCH

Application filed October 26, 1932. Serial No. 639,585.

This invention relates to an improvement in stitches, the object of the invention being to provide a strong, elastic and durable stitch that may be made at high speed and be suitable for a great variety of sewed articles, especially for the seaming of pants and coats that are subject to considerable strain and frequently break and rip.

The crotch seams of pants, sleeve seams, and the back seams of coats give way unless double stitched to make such seams secure. This double stitching means two operations and even then the sewed lines are not uniform or even, so that the two lines of stitches do not equally share in strength because they are not united so as to hold together, consequently, they break, pull out and the seam opens.

This improved stitch overcomes these objections because the needle threads pass through the material side by side i. e. substantially contiguous in staggered or alternate relation and these needle threads are concatenated with a single looper thread in such a way as to provide full strength of the seam equal to the full strength of the material, and such seams will open and lie flat when pressed without showing any ridge after pressing.

Another advantage is that this improved stitch can be made on machines now in use by slight changes in their stitching mechanism, such as the addition of another needle to a single needle machine, means for properly controlling the second needle thread, the provision of needle clearance in the presser foot and throat plate, and a timed relation of the thread carrying looper to co-act with two needles, one behind the other, thus enabling the production of this improved stitch on the machines now in use, especially the well-known Metropolitan sewing machine, in which the looper operates in a path opposed to the direction of the feed of the work. A further advantage of the present invention resides in the fact that the sewing machine is operated at a normal speed to produce twice the work of the usual machine, that is each reciprocation of the needle bar produces two stitches.

This improved stitch has proved to have twice the strength of the single needle United States standard stitch type 401, and the lineal yardage of stitching is twice that of the machine making such type of stitch because the length of stitch or feed stroke can be double that of such old machine.

In the drawing accompanying and forming a part of this specification, Fig. 1 is a view of this improved stitch enlarged to clearly show the concatenation of the threads.

Fig. 2 shows the stitch more closely formed.

Fig. 3 is a top view and illustrates seams having both short and long needle thread stitches.

Fig. 4 is a bottom view of the stitch with the needle loops close together, and

Fig. 5 is a modified form of stitch showing a different needle loop spacing.

Fig. 6 illustrates a seam showing the top and bottom of the work and stitch.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawing since the invention is capable of other embodiments, and that the phraseology which I employ is for the purpose of description and not of limitation.

This improved stitch is made with two substantially contiguous needle threads 1 and 2 as shown in Figure 3 and a single looper thread 6 and these two needle threads are carried through the material by the needles to form needle loops 3 and 4, located in substantial alignment on the under side of the work while the needle stitches 1 and 2 on top of the work are located in alternation or staggered.

Each pair of needle loops passes through a loop 5 of the looper thread 6 extending from the last preceding stitch and this looper thread loop, in turn, passes through a pair of preceding needle loops 3 and 4 of the needle threads 1 and 2 and extends one stitch

length. Thus, a looper loop passes through a pair of needle loops and, in turn, receives a pair of needle loops so that each pair of needle loops not only has extending there-
5 through a looper loop but also passes through another looper loop, the foregoing operations being repeated to form a sequence of stitches.

10 The needle loops 3 and 4 on the under or looper side of the work are in tandem relation or as closely in line as possible, spaced with relation to the direction of the feed of the material with respect to the length of the stitch. That is to say, if the length of the
15 stitch be one-quarter inch and the needles place the loops 3 and 4 one-eighth inch apart, then eight stitches per inch will be placed in the material. This improved stitch also permits different spacing of the needle loops
20 3 and 4. If spaced one-sixteenth of an inch apart, the loops will be that distance from one another regardless of the length of the
25 stitch. Figs. 4 and 5 illustrate this difference of needle loop spacing.

25 Looking at the bottom of the stitch on the material 7, it will be seen that this improved stitch provides a secure anchorage even with the very finest of threads so that a flat smooth stitch is produced with the
30 needle thread loops 3 and 4 drawn well into the material. This improved stitch has greater elasticity and holding power and strength than United States standard stitch type 401 even if that stitch is produced with
35 threads equal in bulk or size to the three threads used in my improved stitch.

Fig. 6 illustrates the improved stitch applied to material 8 having a pinked trimmed edge 9. The material is folded over to show
40 both top and bottom of the stitch and seam.

The arrangement of the tandem needle loops with respect to the direction of the feed of the material may be such as to place the loops 3 and 4 in a line whereby the threads
45 extending from one stitch to the next will be over one another or nearly so. The loops 3 and 4 may also be placed with slight lateral spacing, in which case there will be a space between the threads 1 and 2 lying on the top
50 surface of the material 7.

If the spacing of the needles is equal to one-half the length of the feed stroke, then the needle loop of one of the needles will be placed mid-way between two of the needle loops of the other needle, alternating in this manner so that the spacing of the needle loops on the bottom of the work will be equal distances from one another (see Fig. 4). On the other hand, by varying the spacing of
55 the needles, the stitch may be lengthened or shortened. This difference is shown in Figs. 4 and 5.

In this improved stitch, as clearly shown in Figs. 1 and 2, each group of four needle loops, two loops 3 and two loops 4, complete

a pair of stitches, and each pair of stitches so formed is anchored by reversed formed loops of looper thread, a portion of one of said loops continuing to the succeeding stitches, whereagain it is formed into a re-
70 versed double loop concatenated with the second needle loop 4 and the second needle loop 3.

To complete the stitch requires two cycles of sewing machine movements. That is to say, starting the cycle with the needles at their lowest position where they have formed the first two loops 3 and 4 at the right hand of Fig. 1, the looper thread 6 passes through these two loops as the needles rise. When they have moved clear above the work, the feed of the material advances. Then the needles descend through the material to form the second pair of loops 3 and 4 and as the needles thus descend with these loops of
75 needle thread, they are passed through the left hand end of the first looper thread loop. The looper moves backward out of the first two loops of needle threads 3 and 4 and then again moves forward through the second pair of needle loops 3 and 4 to form the next looper thread loop and so on. The movements are repeated for successive stitches.

It will be clearly understood that in the formation of this improved stitch, the looper thread is anchored to the bottom of the work by each group of four needle loops, whereby a stronger stitch with greater elasticity is produced, and the output of a machine arranged to make this improved stitch is twice
80 as much as that of the ordinary machine.

As before stated, this new stitch makes a very satisfactory seam for pants and coats. It also is very satisfactory for the stitching of shoes, dresses and especially those made
85 from delicate fabrics, and is also very satisfactory for bag stitching for it is an advantage in the seam structures of bags used for
90 fine granular materials such as sugar, salt and the like in that it produces a seam that is less liable to leakage since the needle threads pass in tandem loop formation through the material side by side in staggered or alternate relation and these needle threads are concatenated in the direction of
95 the stitch formation with a single looper thread in such a way as to provide full strength of the seam equal to the full strength of the material. Such seams are thus less liable to leakage if used for bags or similar
100 articles and offer a very strong, elastic seam for delicate fabrics used for wearing apparel. These seams will also open and lie flat when pressed without showing any stitch ridge marking after pressing due to the fact that only one looper thread is used and it is drawn
105 flat against the material where it lies smoothly so that in the operation of pressing the garments, it will not form a ridge and show through on the right side of the material.

It is to be understood that, by describing in detail herein any particular form, structure or arrangement, it is not intended to limit the invention beyond the terms of the 5 several claims or the requirements of the prior art.

Having thus explained the nature of my said invention and described a way of constructing and using the same although without attempting to set forth all of the forms 10 in which it may be made, or all of the modes of its use, I claim:

1. An improved stitch comprising a pair of parallel contiguous rows of needle stitches 15 located in alternation on top of the work with the needle loops on the under side of the work in tandem relation, and a looper loop projecting through a pair of needle loops and 20 through which looper loop a pair of needle loops pass.

2. An improved stitch comprising concatenated needle loops and looper loops, the needle loops being located in tandem relation on one side of the work and the stitches there- 25 of contiguous and in alternation on the oppo- site side of the work, each pair of needle loops receiving therethrough a looper loop, and another looper loop receiving therethrough the same pair of needle loops.

30

3. An improved seam having parallel contiguous rows of needle stitches and comprised of spaced tandem needle thread loops concatenated by a double loop looper thread passing through and around the spaced tandem needle loops, the spaced tandem needle loops having the threads thereof on one side of the work located in alternation. 70

4. An improved stitch comprised of three threads, two needle threads and one looper thread, the needle threads being contiguous and located in alternation on one side of the material and having the loops thereof in tandem relation in the direction of the stitch formation on the opposite side of the mate- 80 rial and a looper thread, the loops passing through and also around the needle thread loops to anchor the stitches to the material.

5. An improved three thread stitch in which alternating needle thread loops pass through the material forming contiguous stitches on one side thereof and are anchored on the other side of the material by a looper thread passing forwardly through two of the said needle loops and then forwardly around the next 90 two needle loops.

Signed at Philadelphia, Pennsylvania,
this 10th day of October, 1932.
